F. BINI.
DEVICE FOR THE PREVENTION OF POCKET PICKING.
APPLICATION FILED JULY 11, 1919.
1,347,005. Patented July 20, 1920.

Inventor:

Francesco Bini
By *Emile Daniels*
Attorney.

UNITED STATES PATENT OFFICE.

FRANCESCO BINI, OF MILAN, ITALY.

DEVICE FOR THE PREVENTION OF POCKET-PICKING.

1,347,005.

Specification of Letters Patent. Patented July 20, 1920.

Application filed July 11, 1919. Serial No. 310,119.

To all whom it may concern:

Be it known that I, FRANCESCO BINI, a subject of the King of Italy, residing at Milan, Kingdom of Italy, have invented 5 certain new and useful Improvements in Devices for the Prevention of Pocket-Picking, of which the following is a specification.

The present invention relates to a device 10 which gives warning of an attempt to steal an object from the pocket by the report of a detonator fixed to the object to be protected, which detonator is discharged by a pull on a small chain attached to the clothes.

15 The device forming the subject of the present invention has for its main objects practicability and ease of application, and to make the detonation certain.

The accompanying drawing illustrates by 20 way of example one form of the invention. This form comprises

(a) A cylindrical casing in several pieces containing a detonating device, the said casing to be fixed to the object to be protected;

25 (b) A detonating device inclosed in the said casing to be actuated by a small chain attached by its loose end to the clothes;

(c) A small chain having its two ends attached, one to the detonator and the other to 30 the clothes, and certain accessories for the purpose of keeping the chain in its proper position.

The casing is composed of two tubular metal cylinders 1—2, joined by a screw collar 3 through which passes the shank of the percussion striker. The upper tube is closed by a screwed plug 4, of which the interior face forms the anvil of the detonator; it is pierced by a number of holes 5 and it carries 35 a retaining spring clip 6 by means of which one can fix the casing to the object to be protected, for example a pocket wallet. The lower tube 2 is closed by a screwed plug 7 which carries the retaining arrangement for 40 the detonator and through which passes the shank of the releasing arrangement.

In the upper tube may be placed a dia- 45 phragm 8 to close the detonating chamber 9.

50 The detonating device consists of a percussion striker and arrangements for retaining and releasing the striker.

The percussion striker comprises a shank 10 held, by the pressure of the spring 11 on 55 the nut 12, against the plug 4, on which is placed the detonating substance. The shank

10 passes through a hole in the center of the screw collar 3 and carries at its extremity a button 13 arranged to engage with the retaining apparatus.

60

The said retaining apparatus comprises several spring hooks, 14 the release of which is controlled by a truncated cone shaped button 15 held in its highest position by a spiral spring 16 and joined to a shank 17 65 carrying link 18 to which is attached one end of the chain 19.

The chain passes through a ring 20 which can be attached to the object to be protected by means of the screw button 21, and then 70 through the clothes, if necessary, by way of eyelets formed of two pieces of metal 22—23 screwed together and having a washer 24 next the material of the garment 25, and then attached by its other end to a ring 27 75 furnished with a screw threaded pin on which screws the nut 29, by means of which the said ring is attached to the clothes.

To put the device in the position to operate, unscrew the plug 4 and place a charge 80 of detonating mixture in the detonation chamber 9 and screw in plug 4. Unscrew the tube 1 from the collar 3 and press back the detonator with the finger until the button on the end of the shank engages with 85 the hooks of the retaining apparatus 14, then replace the tube 1. The device is now fixed by means of the clip 6 to the object to be protected, the chain 19 passed through the hole 20 and attached to the ring 18 of 90 the apparatus. Should a thief attempt to steal the object, he pulls the chain which causes the release arrangement to act caus- 95 ing the detonation, while the object remains attached to the chain by reason of the clip 20 and the ring 20.

What I claim as my invention is:—

1. In a protection device of the class de- 100 scribed, an alarm carrying device comprising a tubular member adapted to carry a charge of detonating material; a detonator extending into said tubular member; a plug in one end of said tubular member for sup- 105 porting said detonator; a second tubular member secured to said plug and into which the detonator extends; a latch in said second tubular member adapted to engage the end of the detonator and hold the same cocked; and a trigger in said second tubular member and extending to the outside thereof adapt- 110 ed to release said latch to permit the detona- 115 tor to strike the detonating charge under

the influence of a tensioned spring, when the trigger is operated.

2. In a protection device of the class described, the combination of a cylindrical casing comprising a plurality of separable parts and having a clip whereby it is attached to the article to be protected; a percussion striker carried by a shank and provided with a spring; a retaining device for

10 the percussion striker comprising a plural-

ity of spring hooks for engaging the shank of the detonating device to hold the same with the spring tensioned; a trip device adapted to release the hooks from the shank, all of said devices being contained within the casing; and means attached at one of its ends to the trip device for operating the same.

In testimony whereof I affix my signature.

FRANCESCO BINI.
